DIAL MECHANISM.

1,136,891.

Specification of Letters Patent.

Patented Apr. 20, 1915.

Application filed June 1, 1914. Serial No. 842,339.

To all whom it may concern:

Be it known that I, ZENAS P. CANDEE, a citizen of the United States, residing at Waterbury, in the county of New Haven 5 and State of Connecticut, have invented certain new and useful Improvements in Dial Mechanism, of which the following is a specification, reference being had therein to the accompanying drawings.

10 This invention relates to a new and improved dial mechanism. It is illustrated in the drawings as applied to a press, but its use is not limited thereto, as it may be applied to a dial of any kind, or used with any 15 other type of machine.

It is the object of this invention, among other things, to provide a simple and easy moving mechanism that will operate the dial positively, with the minimum of wear 20 upon the parts, and lock the same against movement at predetermined periods.

25 To these, and other ends, this invention consists in the dial mechanism, having certain details of construction, and combinations of parts, as will be hereinafter described, and more particularly pointed out in the claims.

30 Referring to the drawings, in which like numerals of reference designate like parts in the several figures; Figure 1 is a view of my improved mechanism as attached to a press, a portion thereof being shown; Fig. 2 is a front elevation of the parts shown in Fig. 1; Fig. 3 is a view of the dial actuating mechanism, looking toward the rear of the press; Fig. 4 is a sectional view of the dial with its adjacent parts, taken upon line A—B of Fig. 1; Fig. 5 is a view of a portion of a modified form of mechanism 35 embodying my invention; and Fig. 6 is an elevation of the pawl and adjacent mechanism, shown in Fig. 5.

40 This invention may be applied to any form of mechanism wherein a rotary dial is requisite, but as herein shown, it is applied to a press of the ordinary type, having a reciprocating gate.

45 It is the practice to operate a rotary dial from a moving pawl connected with a member having an endwise movement in a straight path, and lock the same against movement at predetermined periods by a locking pawl, or similar mechanism, that maintains a permanent contact with the pe-

riphery of the dial and drops into a notch 55 therein when the same is to be held against movement. Both of these operations have proven unsatisfactory, the first because the moving pawl, being operated from a member having a movement in a straight path, 60 causes the pawl to rock within the dial notch, thereby varying at all times the relative positions of the pawl and dial. This causes both the pawl and dial notch to become worn, and in time results in a defective 65 and uncertain movement of the dial and the substitution of a new pawl and dial. The locking pawl dragging against the periphery of the dial, usually under pressure, is an added cause for unusual wear 70 upon the periphery of the dial, which is accentuated if the locking pawl is considerably harder than the dial; and again, the pawl, as it is forced into the notch, wears off the sharp corners of the notch, causing 75 them to become rounded in a comparatively short time, and assisting with the moving pawl to so enlarge them as to entirely ruin the dial.

80 It will be observed that both the moving pawl and locking pawl have a constantly deteriorating effect upon the dial, so that the same in practice is comparatively short-lived. In my invention I have overcome these and other objections by providing an 85 operating pawl that is moved about the center of the dial, and during its entire contact therewith has no relative movement, hence there is no wear upon either the dial or the pawl, and the locking pawl is so designed and operated that it does not bear 90 against the periphery of the dial, but moves into the notch without dragging over the corners thereof. All of this mechanism is so designed and arranged that none of its 95 parts interfere with the punch and die mechanism, which may be inserted in, or removed from, the press without disarranging any portion of the dial mechanism.

100 Referring to the drawings, the numeral 1 designates the bed of a power press, 2 the uprights usually made integral therewith, and 3 a punch that is fixed in a gate (not shown), having a reciprocatory movement toward and away from the bed 1. This 105 mechanism is well known in the art and constitutes no part of my present invention.

Secured to the press bed 1 is a dial bed 4,

having a bushing 6 therein held against rotation by the dowel 7. Rotatable about the upper end of said bushing is the dial 5, which rests upon the dial bed 4, and rotatable about the lower end is a pawl-arm 8.

The dial 5 is provided with the usual peripheral notches 16 and the openings 17 therethrough to carry the articles into line with the punch and die.

10 A washer 10 secured against rotation by the dowel 9 rests upon the dial 5, and is engaged by the friction disk 11 that surrounds the stud 12 held against rotation within the dial bed 4. This stud extends 15 through the bushing 6, and threaded thereon are the nuts 13 and 14, the former of which bears against the friction disk 11, and between the latter and the bushing 6 is a coil spring 15.

20 By the mechanism just described both the pawl arm 8 and dial 5 are held with independently variable friction, the former through the medium of the coil spring 15 and nut 14, and the latter through the friction disk 11 and nut 13. Only a very limited friction is required upon the dial 5. Its weight would be sufficient in most cases, but to insure an operation positive beyond all doubt, only a limited variable friction 25 is applied thereto, which, however, may be materially increased through manipulation of the nut 13.

Connected with the pawl arm 8 upon the pin 18 is the pawl 19, having a tooth 20 35 upon its outer end of substantially the same shape as the notches 16, and an arm 21, to which the swivel block 22 is connected by the pintle 23.

Upon one side of the bed 1 is a journal bearing 24, within which is rotarily mounted a shaft 25, having a cam 26 thereon that rotates in a path substantially parallel with that of the dial 5. Within said journal bearing is a fixed stud 27, upon which is 40 mounted a rock lever 28 having a spring arm 32, a connection arm 30 having a slot 31 therein, and a cam roll 29 rotatable therein that contacts with the periphery of the cam 26.

45 The dial driving lever 33 is pivotally connected with the bed 1 by the stud 34, and is provided with a slot 35 therein, into which projects a roll 36 upon the stud 37 that is fixed to the arm 30 of the rock lever 28 by the nut 38, said stud passing through the slot 31. By this form of connection between 50 the rock arm 28 and dial driving lever 33, means are provided for varying the length of movement of said driving lever and thereby provide adjustment of movement to the pawl 19, with which it is connected through a connection comprising a link 39 pivotally joined with the driving lever 33 by the pintle 40, and the rod 41 that is threaded into 55 the link 39 and passes through the swivel

block 22, with a jam nut 42 thereon that bears against the link 39, and nuts 43 and 44 thereon upon opposite sides of the swivel block 22. A spring 45, between the nut 43 and said swivel block, permits a limited 70 movement of the connection between the driving lever 33 and the swivel block 22, after the dial has come to a full stop. This limited excess movement of the lever 33 and the pawl connection prevents the overthrow of the dial or breakage of any of the parts when the dial is stopped by the locking pawl, in a manner hereafter to be described, this latter element determining the limit of movement of the pawl rather than its connection with the driving lever.

75 The locking pawl is designated by the numeral 46 and terminates at one end in a tooth 47, which is substantially the same shape as the notch 16, and the tooth 20 80 upon the pawl 19. This locking pawl, by means of the stud 49, is pivotally mounted upon a plate 48 adjustably secured to the driving lever 33 by the bolt 50, which passes through a slot 51 in said plate. The relative position of said locking pawl and driving lever is determined by the position of the screw 52 that is threaded through a lug 53 on the driving lever 33, and against the end of which the locking pawl is normally held by a spring 54 between the pins 55 and 56.

85 As the driving lever 33 is moved upon its pivot mounting, the locking pawl 46 moves therewith, and the tooth 47 upon the end 90 thereof travels in a path toward and away from the periphery of the dial 5 and at one end of its stroke enters one of the notches 16, which at the time is in register therewith. If for any reason the dial has not 95 been moved to such position as to present a notch in the path of the tooth 47, the said tooth will contact with the periphery of the said dial and be rocked upon its pivot mounting 49 against the tension of the 100 spring 54, permitting the driving lever 33 to continue its movement without action of the rocking pawl. This relative movement of the locking pawl upon the driving lever 105 33 prevents the breakage of any of the parts if for any reason the dial is not moved to its proper position.

110 Cam roll 29 is held against the periphery of the cam 26, and the driving lever 33 is held under tension in one direction by a 115 spring 58 that surrounds a spring rod 59 between the collar 61 and the nuts 62 and 63. The rod 59 passes through the spring arm 32 upon the rock lever 28 at one end and projects at the other end into an opening 60 120 in the lug 57 upon the driving lever 33.

125 Assuming that the parts shown in Fig. 1 are designated as a zero position, wherein the dial has been moved by the pawl 19 to the limit of its stroke and the tooth 47 on 130

the locking pawl 46 is in register with one of the notches in the dial to prevent further rotation thereof, at this time the punch 3 is moved toward the dial and performs its operation upon the article in the opening 17 that is in register therewith. From this zero position the pawl 19 is moved about the axis of the dial 5, through the movement of the driving arm 33, which first rocks the 10 said pawl 19 upon its pivot mounting 18 until the face 64 thereon contacts with the flat face 65 upon the stud 66 fixed in the pawl arm 8, at which time the tooth 20 of the said pawl has been moved out of its 15 engagement with the notch in the dial. By this action, the tooth 20 does not drag against either side of the notch, and therefore imposes no wear thereon. After the pawl has contacted with the stud 66, the 20 continued movement of the driving arm 33 moves the pawl arm 8 in a rotary path about the axis of the dial, and at the same time withdraws the tooth 47 on the locking pawl 46 out of engagement with its notch, 25 so that the dial is entirely free for a subsequent rotation. During the movement of the pawl arm 8, just described, no portion of the pawl 19 is in engagement with the dial. At the next forward movement of 30 the driving arm 33, the pawl 19 is again rocked upon its pivot mounting 18 and the tooth 20 thereon moved into the notch 16 in register therewith, and the continued movement of said driving arm maintains the 35 said tooth 20 in engagement with said notch and rotates the dial about its axis until the substantial limit of its movement is reached, at which time the tooth 47 upon the locking pawl 46 engages the notch 16, now brought 40 into register therewith. Any additional movement of the driving arm 33, due to faulty adjustment, or other means, is accommodated by the yielding of the spring 45. During this entire movement of the pawl 45 and dial the pawl maintains a fixed position in relation to the dial and has no relative movement in relation thereto.

The die block, designated by the numeral 67, is all below the dial, and can be moved 50 into and out of its operative position without disturbing any of the elements of the feeding mechanism, a very desirable arrangement of the parts, and one not heretofore obtained.

55 In Fig. 5 I have shown a modified form of dial actuating mechanism, wherein the pawl arm 68 is provided with a lug 69 at its outer end, to which a pawl 71 is pivotally secured by a pintle 70. This pawl is 60 also fixed by the screw 73 to a pawl block 72, connected with the driving lever 74 by a rod 75 that passes through a swivel block 76, rotarily mounted within the driving lever 74. Nuts 77 provide means for adjusting 65 the relative endwise position of the con-

necting rod 75. The driving arm 74 and the locking pawl connected therewith are both actuated by the same means as has been heretofore described in the preferred form of structure. In this case the first movement of the connecting rod 75 rotates the pawl block 72, and thereby shifts the pawl 71 upon its pivot mounting and out of engagement with the notch in the dial, and at the commencement of the movement in the 70 opposite direction the first action of the connection 75 is to rotate the pawl 71 upon the pivot mounting in the opposite direction and move the same into engagement with a 75 notch in said dial.

The principal difference between the preferred and modified forms herein shown and described is the fact that in one form means for actuating the pawl arm are between the uprights 2 of the press and in 80 the other upon the outside.

Within the spirit of this invention the details of the mechanism may be very materially altered and still operate within the broad idea of my invention, and I would therefore have it understood, that I do not limit myself to the exact construction herein shown and described, but claim all that falls fairly within the spirit and scope of 90 my invention.

Having described my invention, what I 95 claim as new and desire to secure by Letters Patent, is:—

1. The combination with a dial having one or more stop faces thereon; of a pawl lever movable about the same axis as said dial; a pawl movably mounted upon said lever; means for limiting the movement of said pawl upon said lever in one direction; a rock lever; a second rock lever, having an 100 operative engagement with and actuated by said first lever; means having connection with both of said levers for moving them in one direction; a connection between said second rock lever and said pawl; and a detent connected with one of said levers and movable into and out of the path of the 105 stop faces in said dial.

2. The combination with a dial having one or more stop faces thereon; of a pawl lever movable about the same axis as said dial; a pawl movably mounted upon said lever; means for limiting the movement of said pawl upon said lever in one direction; a rock lever; a second rock lever, having an 115 operative engagement with and actuated by said first lever; means having connection with both of said levers for moving them in one direction; a connection between said second rock lever and said pawl; means for 120 varying the length of said connection; and a detent movably mounted upon one of said levers and movable into and out of the path of the stop faces in said dial.

3. The combination with a dial having one 130

4

or more stop faces thereon; of a pawl lever movable about the same axis as said dial; a pawl movably mounted upon said lever; means for limiting the movement of said pawl upon said lever in one direction; a rock lever; a second rock lever, having an operative engagement with and actuated by said first lever; means having connection with both of said levers for moving them in one direction; a connection between said second rock lever and said pawl; a detent connected with one of said levers and movable into and out of the path of the stop faces in said dial; and means for variably limiting the movement of said detent upon said lever.

4. The combination with a dial having one or more stop faces thereon; of a pawl lever movable about the same axis as said dial; a pawl movably mounted upon said lever; means for limiting the movement of said pawl upon said lever in one direction; a rock lever; a second rock lever, having an operative engagement with and actuated by said first lever; means having connection with both of said levers for moving them in one direction; a connection between said second rock lever and said pawl; a locking pawl pivotally connected with one of said levers; means for varying the relative position of said pivotal connection with said lever; and means limiting the movement of said locking pawl in one direction.

5. The combination with a dial having one or more stop faces thereon; of a pawl lever; a pawl movably mounted upon said lever; and means for applying a variable friction to said dial and to said pawl lever.

6. The combination with a dial; of a pawl lever movable about the same axis as said dial; a pawl movably mounted upon said lever; and means for applying an independently variable friction to said dial and said pawl lever.

7. The combination with a central member; of a dial rotatable thereon; a pawl lever rotatably mounted thereon; a pawl mounted upon said lever; means for maintaining the

contact of said central member with said pawl lever with a variable friction; and independent means for applying a variable friction to said dial.

8. The combination with a central member; of a dial rotatably mounted thereon; a pawl lever rotatably mounted thereon; a pawl movably mounted upon said pawl lever; a member connected with said central member and having two independent spring elements connected therewith; and means for independently varying the tension of said spring members.

9. The combination with a central member; of a dial rotatably mounted thereon; a pawl lever rotatably mounted thereon; a pawl movably mounted upon said pawl lever; a member connected with said central member and having two independent spring elements connected therewith; and means for independently varying the tension of said spring members, one of said spring elements determining the friction upon said pawl lever and the other of said spring elements determining the friction upon said dial.

10. The combination with a dial having one or more stop faces thereon; of a pawl lever movable about the axis of said dial; a pawl movably mounted upon said lever; means for limiting the movement of said pawl upon said lever in one direction; a rock lever; a second rock lever; means for operatively engaging said levers; means for adjusting the relative position of said engaging means, whereby the stroke of said second lever may be varied; a connection between said second rock lever and said pawl; and a detent connected with one of said levers and movable into and out of the path of the stop faces in said dial.

In testimony whereof I affix my signature in presence of two witnesses.
